UNITED STATES PATENT OFFICE

2,550,790

DISPENSER ADAPTED TO DELIVER INDIVIDUAL SHEETS FROM A PERFORATED AND ROLLED WEB

John B. Engel, Green Bay, Wis., assignor to Bay West Paper Company, Green Bay, Wis., a corporation of Wisconsin

Application May 10, 1948, Serial No. 26,086

10 Claims. (Cl. 242—55.2)

1

This invention relates to improvements in dispensers adapted to deliver individual sheets from a perforated and rolled web. My improved dispenser is of the type which is adapted to permit the user to grasp the end of the web and, by pulling the web, rotate the roll for a limited degree, following which the movement of the roll is arrested and the terminal sheet of the web will be torn free. The particular dispenser herein disclosed is designed for dispensing paper towels, but is well adapted to dispense toilet paper and other like products.

The objects of the invention include the provision of a simple and inexpensive but exceptionally sturdy dispenser in which novel and improved mandrel means is provided for the support of the roll for limited rotation, the arrangement being such that the weight of the roll itself returns the roll from its extreme position to its starting point following each operation.

More specifically it is my purpose to provide an extremely simple means for constructing and mounting the mandrel, as will more particularly appear from the following disclosure of the invention.

In the drawings:

Fig. 1 is a view in front elevation of the dispenser embodying my invention.

Fig. 2 is a view thereof in side elevation as viewed from the right in Fig. 1.

Fig. 3 is a view similar to Fig. 2 showing the case pivoted to its open position respecting the back or mounting of the device.

Fig. 4 is a view in elevation of the other end of the device with the case open and the roll in its starting position.

Fig. 5 is a view similar to Fig. 4, the case being illustrated only fragmentarily, and the roll being shown in its stop position.

Fig. 6 is an enlarged detail view in perspective of the special form of mandrel used in this device.

Fig. 7 is a view taken in transverse section on the line 7—7 of Fig. 6.

The back 8 comprises a mounting for the device. It is designed to be screwed to the wall or suspended in any usual or desired manner. At its top it is provided with a catch 9 for the case 10, which is pivoted to the mounting or back by means of pintles 11 at the lower corners thereof.

Projecting forwardly from the opposite ends of the back are spaced brackets 12 and 13, each of which preferably comprises a plate with a heavy marginal reenforcement, the precise nature of which is immaterial to the invention. In the

2

construction illustrated, the reenforcing bead 14 of the plate 12 is continuous about the exposed periphery thereof, while plate 13 has reenforcing beads 15 and 15' which are spaced apart at the front of the bracket to expose the slot 16. The slot 16 extends inwardly and then downwardly at 17 to provide a bearing opening for the pin 18 of the mandrel 20.

The bracket 12 has a hole at 21 which is aligned with the pin 18 of the mandrel and is adapted to receive pin 22. Extending concentrically about the aperture 21 is an arcuate slot 23 in which the pin 24 of the mandrel is engaged, the ends of the slot limiting the extent to which the mandrel may be oscillated about the axis of pins 18 and 22.

The mandrel 20 preferably comprises a plate 25 having oppositely turned marginal flanges 26, 27 (Fig. 7) and provided adjacent its opposite ends with embossed semi-cylindrical channels 28, 29, (Fig. 6) to receive the respective pins 18 and 22. At its lefthand end (as viewed in Fig. 6), the plate 20 has a further channel at 30 to receive the stop pin 24. Plates 31, 32, welded or otherwise attached to the plate 25, are provided with complementary channels to retain the several pins. The plate 25 and the plate 32 desirably have tabs 33, 34, which project at right angles therefrom and to which the end disk 35 is welded. This disk has apertures through which the pins 22, 24 project as shown in Fig. 6.

The case 10 is so designed that when closed as shown in Fig. 2 it encloses brackets 12 and 13. However, the case is provided at its front with a large dispensing opening 37 through which the roll 38 mounted on the mandrel is readily visible to the person desiring to use towels. It will be understood that the roll is made up of a web of paper perforated at intervals to comprise individual sheets readily separable from the web. The user grasps the depending end 40 of the web and draws it downwardly from the position shown in Fig. 4 to the position shown in Fig. 5. This causes the roll 38 to oscillate about the axis of pins 22, 18, which is offset from the true axis of the roll so that the oscillation of the roll causes the roll, in rotating about this eccentric axis, to increase its average elevation.

The withdrawing movement continues to the extent permitted by the movement of the pin 24 in slot 23. When the pin 24 reaches the upper end of slot 23 as shown in Fig. 5, the rotation of the roll is abruptly arrested and that portion of the web which comprises its terminal sheet will thereupon be severed by the continued pull

of the user on the free end portion thereof. As soon as the terminal sheet is severed, the roll 38 will be restored by gravity to the position shown in Fig. 4.

When the paper is exhausted, the case 10 is swung downwardly to the position shown in Fig. 4, whereupon the mandrel is fully exposed for manipulation. The empty mandrel is removed from the brackets by simply lifting its pin 18 from the slots 17, 16 and withdrawing the pins 22, 24 from the bracket 12. A new roll is then placed on the mandrel and the mandrel re-mounted.

The mandrel 20 is preferably made slightly wider than the core opening of the roll. However, being flat, there is plenty of clearance for the core of the roll to become slightly deformed and take an elliptical shape, the elasticity of the roll and the core holding it securely on the mandrel. With the case or cover of the device open as shown in Fig. 4, it is obviously a simple matter for the operator to engage the pin 22 of the mandrel in the opening 21 of the bracket 12 and to engage the pin 24 of the mandrel simultaneously in the lower end of slot 23. The pin 18 at the other end of the mandrel can then be inserted into the slot 16 of bracket 13 and the pin 18 will thereupon drop into the bearing portion 17 of the slot to be firmly positioned therein for oscillatory movement as above described.

The case is preferably provided interiorly with a keeper at 41 (Figs. 1 and 2) which, in the closed position of the case, spans the bearing portion 17 of the slot, thus anchoring the pin 18 securely therein. The roll can be displaced only when the case is open.

What is claimed is:

1. In a device of the character described, the combination with a pair of spaced supports having aligned bearing apertures, one of said supports having an arcuate guideway substantially concentric with said aperture, of an elongated mandrel receivable into the core of a roll of paper and provided at its opposite ends with bearing pins receivable in the aligned apertures of said supports, said mandrel also having means cooperating with said guideway for limiting the oscillatory movement of the mandrel about its said aligned pins, said means and pins being at opposite sides of the center line of the mandrel and the mandrel having work supporting surfaces eccentrically disposed respecting the aligned pins, whereby the mandrel is biased by the work supported on said surface.

2. In a device of the character described, the combination with a pair of supports, one of said supports being provided with a slot opening to its end and having a downwardly recessed bearing portion, the other support having an aperture opposite said bearing portion and having an arcuate guideway substantially concentric with said aperture, together with a mandrel spanning the space between said supports and having a first pin in said slot and an aligned second pin in said aperture and an offset third pin in said guideway.

3. The device of claim 2 in which the second and third pins are at diametrically opposite sides of one end of the mandrel and both off-center from the center line of the mandrel.

4. In a device of the character described, the sub-combination which comprises a mandrel plate of elongated form provided adjacent one of its ends with an embossed channel, a pin projecting from the channel, a retaining plate having a

complementary channel coacting with said mandrel plate and means connecting the mandrel plate and retaining plate to retain said pin.

5. The device of claim 4 in further combination with another projection from said plate at a point laterally spaced from said pin, and another pin at the end of said plate opposite the pin first mentioned and substantially aligned therewith.

10 6. The device of the character described comprising the combination with a mounting back and a case pivoted thereto and having a dispensing opening at its front, of a pair of spaced brackets connected with said back and projecting 15 forwardly therefrom within the case, said brackets having opposing bearing apertures, one of said apertures opening through a slot to the front of its bracket, the other bracket having a second slot of arcuate form substantially concentric with its said aperture, together with a mandrel spanning the space between said brackets and having bearing pins in the respective bearing apertures, said bracket being further provided with a guide pin operating in the arcuate 20 slot as a means of limiting oscillation of the mandrel, the mandrel being freely removable from said brackets upon disengagement of one of its pins from the bearing aperture which has the said slot opening to the end of its bracket.

30 7. A device of the character described comprising the combination with a supporting back and a case pivoted thereto and provided at its front with a dispensing opening, of first and second spaced brackets connected with the back and 35 projecting forwardly therefrom within the case, the said brackets having aligned bearing apertures one of which opens through a slot to the front of the first said bracket, the second bracket being provided with an arcuate slot concentric

40 with its bearing aperture, and a mandrel receivable in a core of a paper roll for the mounting of said roll between said brackets, said mandrel comprising a plate having a terminal disk at one end and a pair of pins projecting beyond said disk and receivable respectively in the bearing aperture and arcuate slot of the second bracket, the said mandrel being provided at its opposite end with another pin movable into and from the bearing aperture of the first mentioned bracket through the slot opening to the end thereof.

45 8. The device described in claim 7 in which said plate is provided with embossed channels for said pins and has complementary retainers with cooperating channels for retaining said pins.

50 9. In a device of the character described, the sub-combination which comprises an elongated mandrel receivable into the core of a roll of paper, said mandrel comprising a flat plate having parallel edges oppositely flanged to provide guide surfaces engaged with the paper roll, axially aligned embossed channels at opposite ends of the plate, a retaining plate at each end 55 of the plate and having complementary embossed channels to overlie said first mentioned embossed channels, and axially aligned pins in said channels and projecting beyond the ends of said plate in the channels by the retaining plates.

70 10. The device of claim 9 further provided with an embossed channel at one end of the plate and laterally offset from said first mentioned channel at the opposite side thereof, beyond the center line of the plate, the retaining plate at 75 said one end of the plate being provided with a

channel complementary with said offset channel, and a projecting stop pin in said last mentioned channel between said retaining plate and said plate.
